& Eggleston

UNITED STATES PATENT OFFICE.

HIRAM TYREE, OF NEW YORK, N. Y.

TOMBSTONE.

1,365,635.

Specification of Letters Patent. Patented Jan. 11, 1921.

Application filed July 12, 1919. Serial No. 310,368.

To all whom it may concern:

Be it known that I, HIRAM TYREE, a citizen of the United States, and residing in the city, county, and State of New York, have invented new and useful Improvements in Tombstones, of which the following is a specification.

My invention relates to tombstones of a fickle material, preferably a vitreous material, and one object of my invention is to provide a tombstone which, while it may be of such material as is substantially indestructible by the elements and hence as imperishable as may be, is so constructed as to be readily assembled and placed, and firmly retained in the earth. Other objects of my invention will appear as my invention is understood.

Speaking generally, my invention from its broader aspect comprises two sections of fickle material, one a memorial section having a horizontal part, and the other an earth engaging section engaging with said horizontal part through which it may be readily affixed to the memorial section by means of a key. Preferably the key is so constructed or so covered as to be substantially unaffected by long exposure to the weather.

In the accompanying drawing and the following description, I have illustrated and described in some detail the best embodiments of my invention of which I am now aware. Figure 1 is a perspective view, partly in section, of the preferred embodiment of my invention. Fig. 2 is a section through a part thereof showing the same embedded in the earth. Fig. 3 is a perspective view of parts of another form of my invention. Fig. 4 is a section thereof showing this form embedded in the earth. Fig. 5 is a perspective view of still a third form of my invention. Figs. 6 and 7 are sectional views showing different forms of keys, such as may be used with my invention.

In the embodiment of my invention shown in Figs. 1 and 2, there is a vertical memorial section 1 suitable for receiving the inscription, etc. This memorial section is provided with a horizontal part 2 integral therewith. This section 1—2 is of a vitreous material, preferably a plastic glass, and embedded therein is a suitable reinforcement 3, in the instance illustrated woven wire, which extends through both the memorial part and the horizontal part of section 1—2 as ap-

pears from Fig. 2. A countersunk vertical passage 5 is provided through the horizontal part 2 as shown in the figures. The base 8 for carrying the memorial section comprises a boxlike structure open at the bottom and like the memorial section is of a vitreous material, preferably plastic glass. It is provided with suitable reinforcement, such as woven wire, disposed in its sides and top. The wall 9 of the base 8 opposite one face of the memorial section is inclined at its lower end away from the opposite side of the base as shown in Figs. 1 and 2. The memorial section and horizontal part 2 thereof are dovetailed in a slot in the top of the base 8. The top of the base 8 is provided with a vertical opening therethrough complementary to the passage 5. With the parts 1 and 8 in their assembled position, a bolt 12 is passed through the passage 5 into the opening in the base 8 below, this passage and the space between this bolt and the walls of the passage 5 and the opening below the same is filled with any imperishable material 13; this may be a vitreous material such as comprises the parts 1 and 8. The exposed surface of the bolt is then covered with the same or any other suitable imperishable material 14, for example lead, whereby a key is provided joining the horizontal part and the base, the exposed surface or surfaces of which are such as to be unaffected by the weather throughout long exposure to the elements. The base 8 and possibly more or less of the memorial section 1—2 being buried in the earth, the tombstone, on account of the nature of the base and the connection between the two parts, is firmly and quite permanently placed.

In the embodiment of my invention of Figs. 3 and 4 there is again the memorial section 1 provided with a horizontal section 2 integral therewith, both of a reinforced vitreous material. The earth engaging section, however, comprises a horizontal bar 18. The bar 18 is placed on the upper surface of the horizontal part 2 and this bar 18 and part 2 are provided with coöperating passages for receiving the screw threaded, reinforced, fickle screw 19 (better shown in Fig. 4) whereby the memorial section 1 and the earth engaging section 18 are firmly and permanently fixed together. This device is designed to be buried in the earth until the upper surface of the section 18 is at

stantially at the level of the earth as shown in Fig. 4.

In the embodiment of Figs. 5 and 6, the memorial section 1 again has the horizontal section 2 integral therewith, both being of a reinforced vitreous material. The key receiving passage through the horizontal part 2 is countersunk and the lower end of the passage is substantially in the form of a truncated cone. The earth engaging section 21 is provided with a rectangular slot 22. Section 21 is also of reinforced vitreous material and at the center of the slot 22 is provided with a truncated cone part 23 corresponding to the truncated conical opening in the horizontal part 2. A bolt 24 is embedded in the section 21 and projects through the center of the truncated conical part 23. In the assembly of sections 1 and 21, the section 1, including its horizontal part 2, are set down in the recess 22 with the horizontal part 2 inclosing the conical part 23. After the two sections have been fixed together by the nut and washer on the bolt 24 as shown, the remainder of the passage in the horizontal part 2 is filled with any suitable material, for example lead, which is unaffected by the weather even after long exposure. As in the case of the embodiment of Figs. 1 and 2, this additional material prevents the destruction of the metal bolt 24 by the elements.

In Fig. 7, I have shown a slightly modified form of the key connection which may be employed with substantially any one of the before described embodiments of my invention. In this form the key passage only partly traverses the earth engaging member 27; it does not pass completely therethrough.

The headed bolt 28 is located partly in this recess in section 27 and partly in the passage in the horizontal part 2. The space outside the bolt and below its head is then filled with any suitable material 29, thereafter the threaded nut and washer are applied and the remainder of the passage in horizontal part 2 is filled with any suitable weather resisting material as before indicated.

While I have thus illustrated and described the best embodiments of my invention of which I am now aware, it will be understood that my invention is not limited to these embodiments but that these embodiments are merely illustrative of my invention. My invention which I desire to secure by Letters Patent is set forth in the following claims:

1. A tombstone comprising a brittle memorial section, a separate enlarged base or earth section, and a key, a lower integral part of the memorial section projecting horizontally therefrom in engagement with said base section and said key fastening said horizontal part to the base section, the exposed surface of the key being protected from the weather.

2. A tombstone comprising a vitreous memorial section, a vitreous base section, and a key, the base section comprising an open box-like structure having a closed top dovetailed into the memorial section and the key passing vertically through a horizontally projecting integral part of the memorial section and into the base to fasten the two sections together.

In testimony whereof, I have signed this specification.

HIRAM TYREE.
